UNITED STATES PATENT OFFICE.

AMOS G. CANBY, OF DETROIT, MICHIGAN, ASSIGNOR TO NATIONAL CAN COMPANY, OF DETROIT, MICHIGAN, A CORPORATION OF MICHIGAN.

RECEPTACLE-DISPLAY HOLDER.

1,093,033.

Specification of Letters Patent. Patented Apr. 14, 1914.

Application filed January 6, 1913. Serial No. 740,522.

To all whom it may concern:

Be it known that I, AMOS G. CANBY, a citizen of the United States of America, residing at Detroit, in the county of Wayne 5 and State of Michigan, have invented certain new and useful Improvements in Receptacle-Display Holders, of which the following is a specification, reference being had therein to the accompanying drawings.

10 This invention relates to a package display stand for vending small articles of merchandise from the original package, and includes means whereby the stand cannot be used for the sale of spurious or counterfeit 15 articles put up in packages or receptacles for which the stand is not intended.

The invention consists in the matters hereinafter set forth and particularly pointed out in the appended claims.

20 In the drawings, Figure 1 is a view in perspective of a stand and packages thereon, that embody features of the invention; Fig. 2 is a plan view of the base or stand itself; Fig. 3 is a view in transverse section through 25 the base; Fig. 4 is a view in transverse section through the base and a package applied thereto; and Figs. 5, 6 and 7 are views in detail showing the arrangement of the stand for a cylindrical package.

30 As shown herein a base 1, preferably of sheet metal, is adapted to be supported in inclined position by suitable means as for example, a down-turned back flange 2 and front flange 3. The sheet is stiffened by 35 side flanges 4. A set of tongues 5 are struck out from the body of the sheet in off-set parallel relation thereto, each set being in alinement with a retaining rib 6. A transversely disposed rib 7, formed up or struck 40 out from the body of the sheet, is placed between the sets of tongues 5. The ribs 6 and 7 are so disposed in relation to the tongues that they bear against the base flanges of 45 applied receptacles as indicated by the dotted lines in Fig. 2.

The receptacles or packages for the stand have their bodies 8 of any preferred cross section and construction with a bottom 9 that is inset slightly and is provided with 50 transverse slots and out-pressed boss portions 10 that admit the tongues 5 of a set and loc' the package in position on the base between the ribs 6 and 7. The bosses 10 are so disposed that the tongues 5 are flush with 55 or below the level of the interior of the

bottom. In the ordinary construction of sheet metal packages, such as herein shown, the formation of the flange joint between the bottom and the side of the receptacle affords sufficient depression of the bottom. Otherwise the bottom is especially formed so that it is inset sufficiently for the purpose. As a matter of convenience the side flanges 4 are so disposed that they act as guides for the ready application of a package or receptacle to the base, causing the slots in the bottom of the receptacle to register with the tongues of the adjacent set so that the receptacle is easily applied without especial effort.

70 Where the receptacle is cylindrical in section as shown in Figs. 5, 6 and 7, ribs 11 and 12 that are segmental to correspond to the contour of the bottom of the receptacle are formed on the base while the tongues 5 are so disposed in relation to the side flanges 4 that the receptacle is readily brought into register therewith. Where the receptacles are used for cigars or like articles the openings or slots through the bottom are 75 immaterial. A false bottom 13 may be applied over the regular bottom, as indicated in Fig. 7, and the slots for the tongues may be formed therein, thus leaving the package 80 itself intact. As a result, a display stand is obtained which holds a package in position for ready removal of the contents while at the same time the package is fully displayed. Any means of supporting the base in a desired position may be used or 85 the base itself may form a component of a vending machine to move in or out of a casing as desired. Or the base may be one of a series of articulated plates forming the 90 part of a conveyer in a vending or advertising device.

95 The device permits the sale of goods from the original package and prevents the use of packages that do not correspond exactly in contour to the original receptacles for 100 which the stand is intended.

Obviously, changes in the details of construction may be made without departing from the spirit of my invention and I do not care to limit myself to any particular 105 form or arrangement of parts.

What I claim is:—

110 1. The combination of a self supporting inclined base provided with projections, and receptacles having outstruck bottom

members adapted to detachably interlock with the projections, said out-struck bottom members being in a plane set in from the plane of the bottom edges of the receptacle, whereby said receptacle can be evenly supported independent of said base.

2. The combination of a self supporting inclined base provided with projections and ribs, and receptacles each having an out-struck bottom member adapted to interlock with the projections, said out-struck bottom member being in a plane set in from the plane of the bottom edges of the receptacle, whereby said receptacle can be evenly supported independent of said base, the ribs adjacent each set of projections bearing against the marginal portions of an applied receptacle.

3. The combination with a base having sets of tongues on the upper face, of receptacles each provided with integral struck-out bottom members adapted to be detachably engaged with a set of the tongues, said out-struck bottom members being in a plane set in from the plane of the bottom edges of the receptacle, whereby said receptacle can be evenly supported independent of said base.

4. The combination of an inclined base, sets of tongues struck up therefrom in offset parallel relation and ribs formed on the base adjacent each set of tongues, and receptacles each having a slotted bottom member adapted to detachably interlock with the tongues when engaged laterally by the ribs, said out-struck bottom members being in a plane set in from the plane of the bottom edges of the receptacle, whereby said receptacle can be evenly supported independent of said base.

5. The combination of a base, sets of offset rigid tongues on the upper face thereof and in a plane parallel with said base, ribs on the upper face adjacent each set of tongues, and guide flanges for each set of

tongues, and receptacles each having a counter-sunk slotted base member adapted to detachably interlock with a set of tongues, when engaged laterally by the companion flange and ribs.

6. The combination of a base, sets of offset rigid tongues struck up therefrom in a plane parallel with said base and ribs around each set, and receptacles each having a bottom member that is slotted to receive tongues, the tongues being substantially flush with the inner face of the bottom member.

7. The combination with a base formed of a sheet metal plate self-supported in inclined position by down-turned front and back flanges and provided with up-turned lateral guide flanges, sets of off-set tongues struck up from the sheet in a plane parallel to said base and ribs pressed up from the plate adjacent each set of tongues, and receptacles each having a countersunk bottom member that is slotted to detachably interlock with the tongues when the lower marginal portions of the receptacle bear laterally against the companion ribs and flange.

8. The combination with a base, and a receptacle supported in an inclined position thereby, of inter-locking means arranged between said base and the bottom of said receptacle and surrounded by the marginal edges of said receptacle whereby said receptacle is retained upon said base.

9. The combination of a self supporting inclined base, a receptacle having marginal edges adapted to rest upon said base, and countersunk means carried by the bottom of said receptacle and adapted to inter-lock with said base above the surface thereof.

In testimony whereof I affix my signature in presence of two witnesses.

AMOS G. CANBY.
